SUCTION BOX FOR TRAVELING SCREEN FILTERS

Irving C. Jennings, South Norwalk, Conn.

Application February 2, 1946, Serial No. 645,101

10 Claims. (Cl. 92—51)

1

The invention is of utility in any art in which a filter screen, driven over a suction box would be useful for thickening material or extracting liquid. For simplicity of exposition, however, a paper making machine will be illustratively disclosed and referred to.

In the manufacture of paper and allied products, particularly on the wet end of a machine known as a Fourdrinier, difficulty has long been experienced with the rapid wear of the wire screens due to the friction between these screen belts and the suction boxes used to remove the water from the pulp. It is necessary, particularly on high speed machines, to renew these screen belts very often, and as the screen belts are expensive this is an important item in the cost of manufacturing paper. Furthermore, the extra power required to operate the Fourdrinier due to this friction is considerable.

A Fourdrinier screen is made in the form of an endless horizontal belt running over a driver drum, usually a suction roll, and idler drums to support and keep it tight. The top or tight side is further supported by free-running table rolls and by several flat boxes, which are boxes rectangular in section in which is maintained a partial vacuum. Paper pulp mixed with a large percentage of water is fed onto the wires at one end. Some of this water drains through the wires as it passes along over the table rolls and a large amount is drawn out by suction as the wires pass over the flat boxes. This screening and felting action forms the sheet of paper, which is further processed in subsequent operations. The tops of the flat boxes which are in contact with the wires are usually of hard wood, sometimes impregnated with tallow or other like material to act as a lubricant in the presence of water. The heavy suction pressure, however, between the rapidly moving wires and the top of the boxes produces a considerable drag, which results in friction and wear. All this is well known in the art.

Many attempts have been made to produce flat boxes equipped with rollers under the wires to overcome these difficulties. These devices have been only partially successful on slow moving paper machines, and nothing has been produced as yet that is satisfactory for high speed machines.

One of the principal troubles in making such a device lies in the fact that the flat box rollers supporting the wire must be close together, or too great a sag of the wire will occur between rollers. This requires rollers of small diameter arranged close to one another. It has heretofore been customary to support such rollers from end bearings

2

only. As commercial paper machines are very wide, requiring rolls ranging from 8 ft. to 20 ft. or more in length, too great a deflection results when small diameter rollers are used. Difficulty has also been experienced in sealing the roller equipped boxes against air leakage.

It is a primary object of the present invention to provide a suction box which is equipped with small diameter rollers and which includes practical means for rotatably supporting rollers at frequent intervals to prevent sagging thereof.

To this end it is an important feature of the invention that the rollers, divided into short, hollow segments, are rotatably supported from thin brackets interposed between the segments, the supporting and bearing structure carried by the brackets being disposed internally of the rollers.

Other objects and advantages will hereinafter appear.

20 This application is a continuation in part of my pending application, Serial No. 561,342, filed November 1, 1944, for Fourdrinier Machine, now abandoned.

Figure I shows a fragmentary top view of my invention;

Figure II is a section taken along the line 2—2 of Figure I, looking in the direction of the arrows;

Figures III and V are sectional views on different scales, taken upon the section line 3—3 of Fig. I, looking in the direction of the arrows, and showing two methods of supporting the rollers;

Figure IV is a sectional view taken upon the line 4—4 of Figure II, looking in the direction of the arrows but with one of the brackets shown in section which is not in the section plane;

Figure VI shows one method of sealing the end of the rollers, this section being an enlarged view of the roller taken along the same lines as in Figure II;

Figure VII is a fragmentary longitudinal section of the seal shown on Figure VI;

Figure VIII is a suction upon the line 8—8 of Figure III, looking in the direction of the arrows;

Figure IX is an elevation of a portion of the wet end of a paper machine showing the location of the flat box unit with relation to the wire;

Figure X is a fragmentary view in front elevation of a sealing device employed in the machine;

50 Figure XI is a sectional view taken upon the line 11—11 of Figure VII; and

Figure XII is a fragmentary, sectional view showing an arrangement in which solid roller segments are employed.

55 Referring to Figure IX, a roller equipped flat

box unit A, is shown as applied to a Fourdrinier paper machine. The unit A is supported by a frame B. An endless screen belt C runs successively upon table rolls D and over rollers F of the unit A. The screen belt C passes thence around a suction or couch roll E by which it is driven. The paper stock comes in from the right on top of the wire C and flows along C until it reaches the box unit A, the interior of which is maintained under a partial vacuum. Details of the suction box unit A are disclosed in Figures I to VIII inclusive. The box itself is a tightly closed structure desirably rectangular in section, consisting of longitudinal channel members I to the bottom of which a plate 2 is affixed.

The channel members I are connected to one another through cross braces 12 and 13 and by end wall members G. The members I and G have top flanges disposed in a common horizontal plane and on these flanges a roll carrying frame is mounted. The frame comprises longitudinal angle irons 15 and transverse angle irons 3. Several rows of relatively small articulated rollers F are supported in the frame. These rollers are sealed on the top by the wire C which is covered by the wet paper stock. The rollers are supported from the angle irons 3, the supporting means extending through the angle irons and having bearing therein. Cover plates 3a at the outer sides of the angle irons 3 seal the openings thus provided in the angle irons. Seals 4 are provided on angle irons 15 to cooperate with the adjacent rollers F for completing the sealing of the suction box. The suction box is connected by pipe H to a vacuum pump not shown. The rollers F are placed as close together as possible while still allowing room for air and water removed from the stock to pass between them into the enclosure, and are made small in diameter.

The individual rollers which form the composite roller F are made short enough to prevent undue deflection. Each individual roller runs on bearings, desirably of the ball or roller type adjacent its opposite ends.

Figures II, III, IV and VIII illustrate one method of mounting and supporting these bearings. In these figures the bearings 9 are mounted on the stationary shaft 7 fixed in end plates 3, and are supported between the rollers by intermediate brackets 5 which rest on the cross braces 12.

The webs 28 of the brackets 5 extend across the end faces of the rollers to form a partial seal and are made narrow so as to enable the ends of the rollers to extend into proximity with one another, thereby obviating sagging of the wires into the space between the ends of the rollers. Each web is continued as a wire-supporting flange at the upper side of the bearing and terminates just within the peripheral bounds of the associated roller segments. The webs 28 are stiffened by side plates 29 located outside the rollers, the web and side plates being integral with one another and with a base 30. The base 30 is secured to the cross brace 12 by screws 35.

The outer races of the bearings 9 are fixed in the rollers by threaded members 48, which turn with the rollers and are formed with drip grooves 41. The grooves 41 conduct water away from the bearing enclosures when the rollers are stationary, and also act as slingers in conjunction with the ends of the rollers to exclude water during the operation of the rollers.

Stationary bushings 8 between the shaft 7 and the brackets 5 position the inner races of the

bearings 9 and hold the rollers in close running relation without contact with the webs 28 and the end angle irons 3. Proper clearances may readily be secured by first fixing and locking one end bushing 31 and shaft 7 in proper relation by a set screw 33 and then adjusting and locking bushing 32 with set screw 34. After this, brackets 5 may be moved to divide the clearance between the rolls and then locked in place by the screws 35. It will be observed (see Fig. III) that the shanks of the screws 35 pass through slots formed in the upper faces of the cross braces 12.

An alternative structure for mounting and supporting the roller bearings is shown in Fig. V. In this structure the rollers are mounted on the shaft 22 by means of collars 25 fixed in the ends of each roller. These collars may be adjusted longitudinally of the shaft and locked in position by any suitable means such as set screws 25a.

The shafts 22 and rollers F mounted thereon are supported by, and turn on, roller bearings 23. The outer bearing members for the end roller are carried by end plates 3 and the intermediate bearings are located in brackets 6. The brackets 6 are fastened to cross-braces 12. A thrust bearing 24 is fixed to one end of the shaft 22 to hold the rollers in proper axial relation with the end plates 3 and the brackets 6. Interior bearing caps 27 are provided which form bearing closures and hold the bearings in place. These caps are formed with grooves 27'. Slingers 26 are provided on the collars 25 and these together with the grooves 27' effectively exclude water from the bearings.

A further alternative structure is shown in Figure XII. In this structure the braces 12, the brackets 6, the interior bearing caps 27, and the bearings 23 may all be exactly the same as in Figure V. Instead of providing a continuous rod 22, and mounting hollow roller segments F upon it through collars 25, solid roller segments 51 are provided, each roller having annular recesses 52 in its opposite ends for the reception of the bearings 23 and of the bearing caps 27. As compared with the showing of Figure V, it is as if the roller segments F, the collars 25 and the rod 22 were made integral with one another and solid, but with the rod 22 divided lengthwise at the middle of each intermediate bearing 23.

Figure XII illustrates the joint between two roller segments. It will be observed that the annular recess 52 is divided by an annular flange 53 corresponding to the slinger flanges 26 of Figure V. Each solid roller segment is formed with a central hub portion 54 which substantially meets the like hub portion of the neighboring roller segment at the middle of the roller bearing 23. In the case of terminal roller segments, an extended hub portion 54 is provided at one end for cooperation with a bearing in one of the frame members 3. In one instance the extended hub portion has the structure shown at the right-hand end of the shaft 22 of Fig. V for cooperating with a ball bearing 24 and a nut 24a as shown in Fig. V.

At each end of the rollers, members 14 supported on the end frame members 3 (see Figures I and II) extend under the screen belt C to a point just inside the edge 36 of the paper stock on the wire. These members are desirably made of synthetic resin or some similar material and their upper faces are formed with a curvature slightly less than that of the sagging wires to permit these members to be worn in by contact with the wire during the initial period of operation. Thereafter a running clearance will be

automatically maintained at this point, which clearance will be sealed by water which comes along with the paper stock or is separately supplied.

The sealing member 4 adjacent to the composite rollers is shown in detail in Figures VI and VII. A member 16 which may be composed of a single piece of material or of several pieces of material fitted together to form a tight joint is fastened to the angle beam 15. A plate 40, Figs. II and IV, is interposed between the members 15 and 1 and between the members 3 and G. The angle beams 15 are held down snugly but movably on the plate 40 by screws 15a which are passed through the plate and through members 1. The beams 15 also fit snugly between the end members 3. Piece 16 partially surrounds the outside of the outer composite roller F and has a running clearance therewith. The plate 40 is formed with upturned arms 40a through each of which an adjusting screw 40b is threaded. The stud 40b is fixed in an abutment 40c on the angle beam 15 and may be operated when the associated screw 15a is loosened to move the angle beam 15 and the seal member 16 which is carried thereby toward the adjacent roller F. After the desired adjustment has been secured, the screw 15a is again tightened and the screw 40b may be retained in adjusted position by lock nuts 40d.

Piece 16 is provided intermediate between its upper and lower margins with a space or channel 17 which extends lengthwise of the piece 16, but is interrupted in the regions opposite the supporting brackets where solid portions 37 are provided. Above the space 17 there is provided a rib portion 17a, and above the rib portion 17a there is provided a channel 19 having discharge openings 20 which extend outward through the angle beam 15. The space 17 is subdivided by partitions 17b through which openings 17c are formed.

Below the space 17 there are successively a rib portion 17d, a channel 17e, a rib portion 17f, a channel 21 and a rib 17g. As illustrated, the channels 19, 17e, and 21 are all coterminous with the channel 17. The solid portions 37 are formed at either side of a roller segment junction with drain passages 38 which lead into the lower part of the suction box. The parts described are repeated for each roller segment.

Water is forced under slight pressure through a conduit 18, being delivered to the space 17 through ports 18a. Water is forced in under sufficient pressure to fill the space or channels 17e, 21 and 19; and to cause a slight surplus of water to escape through drain openings 20 that communicate with the channels 19. In this way, a film of water is maintained between the member 16 and the adjacent roller F to seal the suction box against ingress of air. A limited quantity of water is continuously drawn into the suction box from the space between the member 16 and the adjacent roller F, but the water flows less freely than air, and its volume represents only a minute fraction of the volume of air which would be drawn in between the member 16 and the roller F if the water seal were not provided.

Although the invention as described herein is embodied in a Fourdrinier machine it is evident that the utility of the invention is not limited to paper making. The invention may find utility in any art in which a filter screen driven over a suction box would be useful for thickening material or for extracting liquid. For example, the invention might be used to advantage in the

sugar making industry for withdrawing liquors from the mash.

I have described what I believe to be the best embodiments of my invention. I do not wish, however, to be confined to the embodiments shown, but what I desire to cover by Letters Patent is set forth in the appended claims.

I claim:

1. In a traveling screen filter, a suction box including a series of closely spaced small diameter rollers on which the screen wire runs, each roller being composed of a plurality of hollow, imperforate roller segments arranged end to end, a stationary rod extending continuously through each roller for supporting the same without sagging, supporting means for the rod comprising end supports and intermediate supporting brackets disposed between adjacent roller segments, said brackets comprising thin upstanding webs between adjacent end faces of said segments, anti-friction bearings mounted within each roller segment adjacent opposite ends of the latter for supporting the segment rotatively on the rod, and end closure seals disposed within the opposite ends of each roller segment for preventing access of water to the bearing, the adjacent ends of roller segments being separated from one another by spaces not substantially greater than the thicknesses of the thin intervening supporting brackets, and each roller segment with its bearings and end seals forming a unit through which the supporting rod may be passed.

2. In a traveling screen filter, a suction box including a series of closely spaced small diameter rollers on which the screen wire runs, each roller being composed of a plurality of hollow, imperforate roller segments arranged end to end, a rod extending continuously through each roller for supporting the same without sagging, supporting means for the rod comprising end supports and intermediate supporting brackets disposed between adjacent roller segments, said brackets comprising thin upstanding webs between adjacent end faces of said segments, and anti-friction bearings mounted within each roller segment adjacent opposite ends of the latter for supporting the segment rotatively on the rod, and sealing plugs threaded into the opposite ends of each roller segment for obstructing access of water to the bearings, the sealing plugs being contained within the roller segments, and the adjacent ends of roller segments being separated from one another by spaces not substantially greater than the thicknesses of their intervening supporting brackets, and each roller segment with its bearings and end seals forming a unit through which the supporting rod may be passed.

3. In a traveling screen filter, a suction box including a series of closely spaced small diameter rollers on which the screen wire runs, each roller being composed of a plurality of hollow roller segments arranged end to end, a rod extending continuously through the successive segments of each roller for supporting the same without sagging, supporting means for the rod comprising end supports and intermediate supporting brackets disposed between adjacent roller segments, each bracket including a broad bearing portion adapted to be received within end portions of adjacent roller segments, and a thin upstanding web portion disposed between adjacent end faces of said segments and carrying said broad bearing portion, each bearing portion carrying a roller bearing through which the

rod is rotatively supported from the bracket, sealing members secured to opposite sides of the bearings to protect and correctly position the bearings, and means rigidly connecting each roller segment to the associated rod, the adjacent ends of the roller segments being separated from one another by spaces not substantially wider than the thickness of the thin web portion of the intervening bracket.

4. A suction box as set forth in claim 3, in which the web of each bracket is continued as a flange at the upper side of the bearing and terminates just within the peripheral bounds of the associated roller segments.

5. In a traveling screen filter, a suction box including a series of closely spaced, small diameter rollers on which the screen wire runs, and a sealing member cooperating with a terminal roller of the series, said sealing member having a face conforming generally to the contour of a wide sector of the roller but being formed with a series of longitudinally extending parallel channels or pockets, said box further including end walls and side walls, the latter including a section movable bodily toward and from an adjacent roller, upon which the sealing member is carried, and cooperative with the associated wall portions of the box to maintain the wall unbroken when it is moved toward and from the roller, and adjusting means for shifting said movable wall section to provide a desired clearance between the sealing member and the roller.

6. A suction box as set forth in claim 5 in which a water conduit is connected through said movable wall section to discharge water under pressure into an intermediate channel of the sealing member.

7. In a traveling screen filter, a suction box including a series of closely spaced, small diameter rollers on which the screen wire runs, each roller being composed of roller segments arranged end to end, and each segment having a hollow portion in which a bearing is received, and supporting means for the bearing comprising a wire-supporting bracket interposed between adjacent roller segments, the peripheries of the adjacent ends of roller segments being separated by a space of substantially less width than the width of the associated bearing portion, said bracket including a thin upstanding web disposed between adjacent end faces of said segments.

8. In a traveling screen filter, a suction box including a series of closely spaced, small diameter rollers on which the screen wire runs, each roller being composed of a plurality of roller segments arranged end to end, supporting means for the segments comprising end supports and intermediate supporting brackets disposed between adjacent roller segments, each bracket including a thin upstanding web disposed between adjacent end faces and a broad bearing portion adapted to be received within end portions of adjacent roller segments, and each carrying a roller bearing through which the roller is rotatably supported, the peripheries of the adja-

cent ends of roller segments being separated by a space of substantially less width than the width of the associated bearing portion.

9. In a traveling screen filter, a suction box including a series of closely spaced, small diameter rollers on which the screen wire runs, each roller being composed of a plurality of roller segments arranged end to end, supporting means for the segments comprising end supports and intermediate supporting brackets disposed between adjacent roller segments, each bracket including a broad bearing portion adapted to be received within end portions of adjacent roller segments, and each carrying a roller bearing through which the roller is rotatably supported, each bracket including a thin web portion disposed between adjacent end faces of said segments and through which the relatively broad roller bearing is carried, said web being continued as a flange at the upper side of the bearing and terminating just within peripheral bounds of the associated roller segments, the peripheries of the adjacent ends of roller segments being separated by a space of substantially less width than the width of the associated bearing portion.

10. In a traveling screen filter, a suction box including a series of closely spaced small diameter rollers on which the screen wire runs, and a sealing member cooperating with a terminal roller of the series, said sealing member being composed of segments arranged end to end, each segment having a face conforming generally to the contour of a wide sector of the roller and having a series of longitudinally extending parallel channels in said face terminating short of the ends of the segment, the box including side walls having an upper longitudinal section carrying said sealing member, said section and sealing member being movable toward and from said terminal roller and adjusting means for shifting said movable wall section and sealing member to provide a desired clearance between the sealing member and the terminal roller.

Certificate of Correction

Patent No. 2,536,446

January 2, 1951

IRVING C. JENNINGS

It is hereby certified that error appears in the printed specification of the above numbered patent requiring correction as follows:

Column 7, line 46, after the word and comma "segments," insert *said bracket including a thin upstanding web disposed between adjacent end faces of said segments,*; line 49, beginning with the comma and word "said" strike out all to and including "segments" in line 51;

and that the said Letters Patent should be read as corrected above, so that the same may conform to the record of the case in the Patent Office.

Signed and sealed this 27th day of February, A. D. 1951.

[SEAL]

THOMAS F. MURPHY,
Assistant Commissioner of Patents.
